LAST

Forrest B. Dennett, Lynn, Mass.

Application May 13, 1930. Serial No. 451,986

3 Claims. (Cl. 12—135)

The invention relates to improvements in lasts of the type in which the toe part moves upwardly and to the rear so the shoe can be removed without undue strain. The invention consists of a heel part and a fore part cut on a circle, in such a manner as to permit the shoe to move away from the heel of the last thereby eliminating all strains. The invention further consists of operating parts or plates which slide in relation to each other having pins operating in the slots which are eccentric with the curve surface dividing the two parts of the last, which will cause the fore part of the last to move away from the heel part thus eliminating all frictional tendency between the two parts. The invention further consists of detailed construction which will be taken up hereinafter.

The object of the invention is to provide a special device which will allow a shoe to be removed from the last without undue strain or trouble and at the same time provide a last which is durable and cheap to manufacture.

Referring to the drawings:

Figure 1 is a side elevation of the last cut in two parts with the shoe in position showing and the mechanism in dotted lines.

Figure 2 is a side elevation of the two part last partly in section showing the fore part of the last in the upward position with the shoe showing dotted lines ready to be removed.

Figure 3 is a partial plan view of the last showing the plates in full on the surface of the last and the dividing line to distinguish the heel part and the fore part of the last.

Figure 4 is a partial underplan view of the last showing the plates in outline and the dividing line between the heel part and the fore part of the last.

Figure 5 is a cross section of the last as shown in Figure 2.

Figure 6 is a side elevation of the plates showing the slots which give direction to the forward plate in its upward movement to remove the frictional tendency.

Figure 7 is an end elevation of the same with a portion of the last broken away and in section line with the pins for holding the plates in position.

Figure 8 is a cross section across the plate showing the pins for guiding the forward plate in its upward position.

Figure 9 is a cross section across the plate showing the pin for guiding the plate.

Figure 10 is a cross section across the plates showing the pin for holding the latch.

The improved last shown on the drawings com-

prises a fore part 10 and a heel part 11, having curved abutting surfaces 12 and 13 which under working conditions are locked together as a rigid construction. Figure 1 illustrates the last, with a shoe 14 mounted in position indicated by dotted lines. It is understood that the upper of the shoe can be readily placed in position on the last for the various operations, but it is only by special devices that the shoe can be removed after the lasting operation without bending the shank 65 causing undue strains on the various parts and distorting the form of the shoe. It is to obviate these conditions that the subject matter of the invention relates. The heel part of the last is provided with two supporting holes 15 and 16 70 provided with metal linings 17 and 18. The last is supported by a jack having a pin 19. The pin 19 is used in both holes, one of which is to support the last during the lasting operation and the other hole is used to remove the shoe from 75 the last after it has been operated upon, this is accomplished by inserting the jack pin 19 into the hole 16 which acts against a latch for unlocking the fore part and the heel of the last so the shoe can be removed and will be described 80 hereinafter. Cut in the fore part 10 and the heel part 11 of the last, concentric with the two curved abutting surfaces 12 and 13 are slots 20 and 21. The former is adapted to receive a double plate construction with a circular slot between 85 them, in which slides a single circular plate located in the slot 21 for guiding the upward and rearward movement of the fore part of the last 11 to facilitate the removing of the shoe from 90 the last. The double plate structure in the heel part 10 is made of two plates 22 and 23 and held apart by the spacing plates 24 and 25 thereby providing a working slot 26 for the single plate 95 in the fore part of the last. This structure is made of metal and is readily secured to the wooden last by the elongated pins 27 and 28. These spacing plates 24 and 25 in addition to the elongated pins 27 and 28 are held rigidly to the side plate by pins 29 and 30. Cut in the plates 22 and 23 are depressions 31 adapted to receive 100 the lining 18 and jack pin 19 so it will operate a latch for unlocking the two parts of the last preparatory to removing the shoe. Located in and in working circular relation to the slot 26 is a single circular plate 32 held rigidly in position to the fore part of the last 11 by the elongated pins 33 and 34. Formed in the stationary plates 22 and 23 are circular slots 35 and 36 respectively adapted to guide the pin 37 in its 105 upward movement and which is rigidly secured 110

to the swinging single plate 32 and held at all times in swinging relation to the heel part of the last. The pin 37 is made with a head having an exact diameter of the slot in which it travels, the 5 pin part is of a smaller diameter but with sufficient length to form a corresponding head on the opposite side of the plate 32 with a diameter of the same dimension as the slot in which it runs. It can be readily seen that this makes a very 10 durable construction as the guide pin is readily secured to the plate 32 while the enlarged ends have a running fit in the slot 35 and 36. With the guide plates rigidly secured to the slot in the heel part of the last makes a very rigid construction. Formed in the plate 32 is a circular 15 slot 38 adapted to receive a pin 39 which is free to slide in the slot 38 of the plate 32. The ends of the pin are of smaller diameter and are riveted to the plates 22 and 23 which makes a rigid and 20 durable structure. The slots and pins mentioned hereinbefore determine the path of the fore part of the last in its upward and forward movement for removing the shoe. In carrying out the invention the two parts of the last are divided by 25 two circular abutting surfaces which when closed must fit perfectly and accurately and when the upward movement of the fore part of the last takes place it must not only move upwardly but away from the rear part of the last thus avoiding 30 friction caused by any swelling of the wood which is liable to happen due to dampness. This double functioning of the fore part of the last is accomplished by making the two circular slots a trifle eccentric to the circular line cutting the 35 last and when the fore part of the last moves upwardly the pins in the slot will guide the fore part of the last away from the heel part as indicated in Figure 6 shown by the dotted lines 40. It is to be understood that when the two parts of the last 40 are together they must fit perfectly but as the fore part of the last moves upwardly the pins in the slots gradually move the abutting surfaces away from each other thus avoiding any trouble or delay in the operation of removing the shoe 45 from the last.

The fore part of the last and the heel part of the last when closed are locked together by a novel means. Mounted between the metal plates 22 and 23 is a latch 41 fulcrumed at 42, 50 the rear end of this latch is constantly pressed upwardly by the spring 43 which is anchored in a right angle slot 44 in the spacer plate 25. The opposite end of the spring is U shaped one side of which rests against the bottom of the slot 55 21 while the other side constantly acts against the rear part of the latch 41 forcing the opposite end downwardly into the supporting hole 16 when the jack pin is removed.

Cut in the lining 16 at its upper end is a slot 60 45 to allow the latch 41 to be operated on by the jack pin 19, this structure can be made in various ways but the device as shown having a slot of the same dimension as the slot cut in the wood facilitates manufacture. After the lining 65 16 is placed in position the slot in the wood and the slot in the lining 16 is cut at the same time leaving a free space for the latch 41 to operate in.

It can be seen in Figure 2 that the latch 41 is held downwardly by the jack pin 19. When the circular plate 32 of the fore part of the last is 70 swung down into the heel part the two parts of the last will remain unlocked until the jack pin 19 is removed. The pivotal pin 42 Figure 10 is of smaller diameter on their outer ends forming 75 a shoulder which allows the pin 19 to be

riveted to the plates 35 and 36 thereby making a rigid construction. The latch has a free running surface on the pin 42 in its operation. Co-operating with the latch 41 is a catch 46 formed in the circular plate 32. The plate moves down into position as shown in Figure 1 and is readily seen that the two parts are locked together and cannot be separated until the jack pin 19 is forced into the hole 16 which pushes the latch 42 out of the catch 46 thus completing the control structure of the two parts of the last.

In operation the upper and sole are placed on the last to be joined together. The last is supported by the jack pin 19 being placed in the supporting hole 15. In this position it is obvious that the heel part of the last 10 and the fore part 11 are locked together as a rigid structure as shown in Figure 1. After the shoe is finished it must be removed from the last and the operation has been the cause of one of the greatest difficulties to remove the shoe from the last without straining the shank. This is due to the fact that the curve surface of the last is gripped by the curve surface of the heel of the shoe and to force the heel by the last causes undue strain 100 and trouble. To offset this difficulty a special device has been formed consisting of cutting the last laterally on a curve line indicated by the surfaces 12 and 13. When the fore part of the last is moved upwardly on a curved line the relation of the curve is such as to move the fore part of the last and the shoe backwardly. This upward and backward movement of the fore part of the last allows the curve surface of the heel of the shoe to move away from the curve surface of the heel of the last. The upward movement causes the top of the shoe to be removed with quickness and dispatch. The upward and backward movement of the shoe and the fore part of the last allows the shoe to be removed 110 with readiness but to obviate the sticking by friction of the abutting surfaces 12 and 13 the slots 35 and 36 in the plates 22 and 23 and in the slot 38 in the plate 32 are cut a little eccentric from the abutting surfaces 12 and 13 which causes 120 the fore part of the last to move away from the heel part in its upward movement. When the two parts are brought together again they fit perfectly thus allowing the two parts to be arranged symmetrically and when separated all 125 frictional tendency will be removed.

When the heel part of the last and the fore part are locked together they must be locked rigidly in position, this is accomplished by a latch 42 cooperating with the catch 46 which holds it 130 permanently in position until the jack pin 19 is forced against the latch 42 releasing it from the catch 46 which allows the fore part of the last to move upwardly and rearwardly so the shoe can be removed. The latch 42 is constantly 135 pressed upwardly by the spring 44 which allows the latch to be forced into place, in the catch 46 by the spring 43 when the jack pin 19 is removed.

What I claim is new and desire to secure by 140 Letters Patent of the United States is:

1. In a last made in two parts having two abutting surfaces, forming, a heel part, a fore part guiding plates provided with slots in the heel part, a single slotted guiding plate in the fore 145 part of the last, pins for guiding the plates, a latch in the slotted plates, a catch formed in the single plate for locking the two parts of the last together.

2. In a last made in two parts having two 150

curved abutting surfaces, forming a heel part, and a fore part, guiding plates provided with slots in the heel part, a single slotted guiding plate in the fore part of the last, pins running in the 5 slots for guiding the plates, a spring pressed latch in the guiding plates, a catch formed in the single plate for locking the two parts together, the last provided with a hole to allow the spring pressed latch to be operated.

10 3. In a last made in two parts having two curved abutting surfaces, a heel part of the last having a slot cut therein, stationary guiding plates secured to the sides of the said slot provided with eccentric operating slots, a fore part of the last

having a single guiding plate provided with an eccentric operating slot working between the double guiding plates in the heel part of the last, a pin secured to and extending through the single plate and a pin secured to the double plate, 80 extending across the space between them operating in the slot to allow an eccentric movement between the said slots and the abutting surfaces to cause the fore part of the last to free itself from the heel part during the upward movement and draws them together at the seating position during the downward movement to prevent friction between the two last members.
